DISPENSER

Thadeus K. Podwyszynski, Brooklyn, N. Y.

Application July 1, 1936, Serial No. 88,310

1 Claim. (Cl. 221—106)

My invention relates to improvements in dispensers, particularly to a dispenser of soap powder and other powdered or pulverized material as for instance talcum, bath salts, or the like in certain predetermined quantities, and it is the principal object of my invention to provide a dispenser of simple and inexpensive construction, yet durable and highly efficient in use.

Another object of my invention is the provision of a dispenser of this type including a container for the material to be dispensed equipped with a means to readily and conveniently secure the same to wooden or tiled walls etc. by means of vacuum cups, rubber cement or the like.

Still another object of my invention is the provision of a dispenser, the container of which may be made from plastic material or metal casting in any suitable form or shape and color, and of convenient sizes.

A further object of the invention is the provision of a dispenser for powdered or pulverized materials including a star wheel forming a plurality of compartments of preferably triangular cross-section of substantially equal capacity adapted to be filled with the material so that during the rotation of the wheel a predetermined quantity of the material may be dispensed through a lower opening in the container or annex thereto, while the outer edges of the partition walls of the star wheel simultaneously serve to loosen the material in the container if the same has become clogged or caked therein.

A still further object of my invention is the provision of a dispenser for pulverized material the star wheel of which may have one or more dispensing compartments and is operated by means of a suitable handle the spindle of which is preferably screwed into the body of the star wheel.

These and other objects and advantages of my invention will become more fully known as the description thereof proceeds, and will then be specifically defined in the accompanying drawing and claim.

In the drawing forming a material part of this disclosure:

Fig. 1 is a sectional side elevation of a dispenser constructed according to my invention.

Fig. 2 is a section through the same on line 2—2 of Figure 1.

Fig. 3 is a cross-section on line 3—3 of Figure 2.

Fig. 4 shows a modified form of star wheel.

As illustrated, the dispenser constructed according to my invention comprises mainly a container 10 for the material to be dispensed, prefer-

ably circular in cross-section and made of any suitable material the upper end of which is closed by means of a removable cover or lid 11 having an inner depending flange 12 tightly fitting against or engaging the inner wall of the container. A handle or grip 13 facilitates the operation of the lid.

The bottom part of the container is preferably substantially hopper-shaped, as at 14, and carries a substantially trough-shaped member 15 attached to the container by means of the screws 16 or the like.

The bottom 14 has a median opening 17 formed therein in alignment with and oppositely disposed to an opening 18 in the trough-shaped member 15, and the material of the bottom at the inner end of the opening therein is bent out of the plane thereof to form a hood 19 so as not to interfere with the free rotation of the blades of the star wheel 20.

This star wheel has preferably, as here shown four blades 21 forming between two adjoining blades compartments 22 substantially triangular in cross-section and of like capacity to receive and dispense a predetermined quantity of the material to be dispensed.

Within the trough-shaped member 15, the star wheel carries a circular disc 23 to which the inner ends of the blades are secured and which rotates with the star wheel upon its operation by a screw 30 or spindle 24 attached to the star wheel's body and carrying an outer handle or knob 25 by means of which the star wheel is rotated.

The attachment of the container to a wall 26, Figure 1 is preferably effected by means of the suction cups 27, 28 respectively, the spindles or studs 29 of which extend into the container through its slotted wall as at 29 and are secured in place by means of heads 30 or nuts 31.

In the form of star wheel illustrated in Figure 4, the wheel 32 has formed therein one compartment only, designated 33.

The use and operation of my dispenser will be entirely clear from the above description thereof by simultaneous reference to the drawing, and it will be evident that any material filled through the top opening of the container after removal of its cover will gradually fill the compartments of the starwheel when the same is rotated with a quantity of material determined by the size of the star wheel compartments formed by the blades. The material will then be dispensed through the lower opening of the trough-shaped element or member, the hood formed with the bottom will in no way allow an interference with the free

rotation of the star wheel, and the suction cups will allow a ready attachment of the dispenser to any support particularly when assisted by rubber cement.

5 It will be understood that I have described and shown the preferred form of my invention only as an example of the many possible ways to practically construct the same and that I may make such changes in its construction and its 10 minor details as come within the scope of the appended claim without departure from the spirit of my invention.

Having thus described my invention, what I 15 claim as new, and desire to secure by Letters Patent is:

In a dispenser for powdered soap a substantially circular container for the soap, a lid for

said container and a bottom for said container having substantially hopper shape and an opening, a hood formed by bending the material of the hopper bottom out of its plane at the inner end of the opening in said bottom, a star wheel having four blades, one of said blades closing the opening in the bottom of the container with the star wheel at rest, said blades shaped to loosen clogged material during the rotation of the star wheel, a disc to which said blades are secured and turning in said hood, a spindle for the star wheel and a handle on said spindle, and a substantially trough-shaped annex to the container having an opening and attached to the container in which the blades and disc are located. 10 15
